(57) **CLAIM**

The ornamental design for the electronic cigarette assembly, as shown and described.

DESCRIPTION

FIG. 1 is a perspective view of an electronic cigarette assembly wherein an atomizer as component 1 and a power supply as component 2 are shown in an assembled state of use;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is an enlarged top plan view thereof;

FIG. 8 is an enlarged bottom plan view thereof;

FIG. 9 is an enlarged perspective view of component 1, the atomizer removed from the electronic cigarette assembly in FIGS. 1–8 for clarity of disclosure;

FIG. 10 is another enlarged perspective view thereof;

FIG. 11 is an enlarged front elevational view thereof;

FIG. 12 is an enlarged rear elevational view thereof;

FIG. 13 is an enlarged left side elevational view thereof;

FIG. 14 is an enlarged right side elevational view thereof;

FIG. 15 is an enlarged top plan view thereof;

FIG. 16 is an enlarged bottom plan view thereof;

FIG. 17 is an enlarged perspective view of component 2, the power supply removed from the electronic cigarette assembly in FIGS. 1–8 for clarity of disclosure;

FIG. 18 is another enlarged perspective view thereof;

FIG. 19 is an enlarged front elevational view thereof;

FIG. 20 is an enlarged rear elevational view thereof;

FIG. 21 is an enlarged left side elevational view thereof;

FIG. 22 is an enlarged right side elevational view thereof;

FIG. 23 is an enlarged top plan view thereof;

FIG. 24 is an enlarged bottom plan view thereof;

(Continued)

FIG. 25 is an enlarged view of area 25 circumscribed in FIG. 1;

FIG. 26 is an enlarged view of area 26 circumscribed in FIG. 1; and,

FIG. 27 is an enlarged view of area 27 circumscribed in FIG. 1.

The broken lines consisting of evenly spaced dash lines in the drawing depict portions of the electronic cigarette assembly that form no part of the claimed design. The broken lines consisting of short and long dashed lines encircling the enlarged detail views are for annotative purposes that form no part of the claimed design.
